US0D1072486S

(12) **United States Design Patent** (10) Patent No.: **US D1,072,486 S**
(45) Date of Patent: ** Apr. 29, 2025

(54) **TOTE LID**

(71) Applicant: **CREATIVE PLASTIC CONCEPTS, LLC**, Sycamore, OH (US)

(72) Inventors: **Jacob H. Whitta**, Bluffton, OH (US); **Ben Sayalith**, Findlay, OH (US); **Eric Hummel**, Findlay, OH (US)

(73) Assignee: **CREATIVE PLASTIC CONCEPTS, LLC**, Sycamore, OH (US)

(**) Term: **15 Years**

(21) Appl. No.: **29/859,485**

(22) Filed: **Nov. 10, 2022**

(51) LOC (15) Cl. **03-01**

(52) U.S. Cl.

USPC **D3/323; D3/318**

(58) **Field of Classification Search**
